UNITED STATES PATENT OFFICE.

FREDERICK WESTPHAL, OF NEW YORK, N. Y.

NONREFILLABLE BOTTLE.

Application filed February 7, 1928. Serial No. 252,453.

This invention relates to a non-refillable bottle and it is the object to provide a device for preventing the introduction of liquids in a bottle when once emptied.

5 The principal object of the invention is to provide a device of this nature having a check valve which will permit the contents of the bottle to be poured out and which will prevent any liquid from entering the empty

10 bottle.

Other objects will appear as the disclosure progresses. The drawings are intended merely to indicate a possible embodiment of the invention it is therefore not intended to limit 15 the invention to the embodiment illustrated but rather to define such limits in the appended claims.

For a more general understanding of the invention attention is now called to the drawings in which a preferred embodiment is 20 shown illustrated.

Fig. 1 is a cross section of a neck of a bottle showing the device attached therein.

Fig. 2 is a section on line 2—2 of Fig. 1.

25 Fig. 3 is a section on line 3—3 of Fig. 1.

Fig. 4 is a section on line 4—4 of Fig. 1.

Fig. 5 is a section on line 5—5 of Fig. 1.

Fig. 6 is a section on line 6—6 of Fig. 1.

30 Fig. 7 is a front view of the plug.

Fig. 8 is a view of the cup partly in section.

Fig. 9 is a perspective view of the valve.

Referring now to the drawings in detail in which like reference characters denote like parts throughout the specification numeral 1 35 represents the neck of a bottle in which is placed the non-refillable device consisting of a cup 2 wedged in place by a sleeve 3 made of cork or a like material. Fastened within this sleeve at the top is a plug 4 and loosely resting at the bottom of the cup is a valve 5.

The plug is provided with three vertical slots, numeral 6 at the neck thereof and three flattened portions numeral 7 at the crown thereof. Means are provided to lock the cup 45 and plug together which consists of slot 8 formed in the neck of the plug and adapted to co-act with a set of three lugs numeral 9 formed in the cup 3.

When inserting the plug 4 within the cup, 50 the plug is first positioned so the slots 6 will register with the lugs 9 of the cup, the plug is then pushed inwardly of the cup and then

given a twist so the lugs 9 will rest in the slot 8 midway of the vertical slots 6 as shown in Fig. 4.

In practice the entire unit is assembled 55 with the parts in relative position and then forced in by a suitable tool in the neck of the bottle, the bottle of course first being filled with the liquid.

When the bottle is inverted for the purpose 60 of emptying its contents the valve 5 will move away from the hole 10 in the bottom of the cup 2 and allow the liquid to pass through the vertical slots 6 and by the flattened portions 65 7 of the plug and thence out from the bottle neck opening. As will be seen from Fig. 1 it will be impossible to normally fill the bottle when once emptied as the valve 5 will act as a check and thus prevent the liquid from passing 70 through the hole 10 into the bottle.

Having thus described my invention, I 75 claim:

1. In a device of the class described, the combination of a bottle neck, a resilient sleeve 75 inserted in said bottle neck, a cup supported by said sleeve, a plug in said cup, means for holding the plug in place, said means consisting of a set of three indentations formed in the wall of the cup and adapted to co-act with a slot formed in the neck of the plug for locking the said cup and plug together, a valve resting in the bottom of the said cup above an opening therein, a series of vertical slots in the neck of said plug and a series of flattened portions in the crown of said plug, said valve when the bottle is tilted adapted to admit liquid through said hole in the bottom of the cup and thence to the vertical slots and said flattened portions, and thence to the neck 80 opening of the bottle, said valve when the bottle is in its upright position adapted to prevent any liquid from entering the bottle.

2. In a device of the class described, the combination of a bottle neck, a resilient sleeve 95 inserted in said bottle neck, a flanged cup supported within said sleeve, a plug in said cup, means for holding said plug in place, said means consisting of a set of three indentations formed in the wall of the cup and adapted to co-act with a slot formed in the neck of the plug and adapted to lock the cup and plug together, a valve resting in the bottom of said cup above an opening therein, a se- 100

ries of vertical slots formed in the neck of said plug, the depth of said vertical slots being greater than the depth of the first mentioned slot, and a series of flattened portions in the crown of said plug, said valve when the bottle is tilted adapted to admit liquid through said hole in the bottom of the cup

and thence to the vertical slots and said flattened portions, and thence to the neck opening of the bottle, said valve when the bottle 10 is in its upright position adapted to prevent any liquid from entering the bottle.

In testimony whereof I affix my signature.
FREDERICK WESTPHAL.
